UNITED STATES PATENT OFFICE.

MILTON M. BETTERLY, OF BYRON, MICHIGAN.

ADVERTISING DEVICE.

Application filed August 29, 1924. Serial No. 735,039.

To all whom it may concern:

Be it known that I, MILTON M. BETTERLY, a citizen of the United States, residing at Byron, in the county of Shiawassee and State of Michigan, have invented new and useful Improvements in Advertising Devices, of which the following is a specification.

This invention relates to an advertising device, the general object of the invention being to provide a casing containing an endless strip supported on rollers in the casing and arranged to appear at a transparent part of the casing when one of the rollers 10 turn so that advertising matter on the sheet or strip can be brought in front of the transparent part so that it can be read.

Another object of the invention is to provide a door which can be opened to expose 20 a part of the strip so that advertising matter can be placed thereon.

A further object of the invention is to provide coin controlled means for opening the door so that the person desiring to place 25 advertising matter on the strip must first deposit a suitable coin before the door can be opened to permit the matter to be placed on the strip.

This invention also consists in certain 30 other features of construction and in the combination and arrangement of the several parts, to be hereinafter fully described, illustrated in the accompanying drawings and specifically pointed out in the appended 35 claims.

In describing my invention in detail, reference will be had to the accompanying drawings wherein like characters denote like or corresponding parts throughout the several views, and in which:—

Figure 1 is a front view of the device.

Figure 2 is a side view thereof.

Figure 3 is a plan view.

Figure 4 is a longitudinal sectional view.

Figure 5 is an enlarged sectional view 45 showing the coin controlled means with the door in open position.

Figure 6 is a similar view but showing the door in closed position.

Figure 7 is a view of one end of the coin receiving roller.

Figure 8 is a detail sectional view showing the pin connection between two parts of the casing.

55 In these views, 1 indicates an L-shaped

casing which has its front face formed in part of a transparent plate 2 and which has a window 3 and a hinged door 4 in the upper face of its horizontal part. A table 5 is arranged under the door and an endless strip 6 is placed in the casing and passes over a large roller 7 on the horizontal part thereof and over the guiding rollers 8 so that a portion of the strip will appear in rear of the transparent member 2 so that advertising matter on said strip can be read through said transparent member. By arranging the guiding rollers as shown in Figure 4 a strip of great length can be placed in the device. This strip passes over the 60 table 5 so that when the door 4 is opened advertising matter can be written or otherwise placed on the sheet, the table 5 supporting the part of the sheet receiving the advertising matter. The roller 7 is provided 65 with a crank handle 9 so that it can be turned to bring new portions of the strip in front of the transparent member and the transparent part of the window 3 may contain directions for operating the device. The window 3 and the lower front 10 of the casing are removably held in place by the pins 11 engaging recesses 12 and the locks 13, the pins being arranged at one end of 70 each of the members 3 and 10 and the locks at the other end. The door 4 engages a cut-out part at the inner edge of the window. The rear of the case may be made in the 75 form of a hinged door as shown at 13'.

I use coin controlled means for preventing 80 the door 4 from being opened until a suitable coin has been dropped in the device. Such means comprises a pair of toothed spaced members 14 on the roller 7, the teeth of which are designed to receive opposite 85 edges of a coin so that the coin will bridge the space between the members and thus act as an abutment which engages the end of an angle bar 15 which is movably held to one side of the casing by the pins 16 engaging 90 the slots 17 in the two parts of said bar. This bar is connected by a clip 18 with a rod 19 which has its inclined ends connected 95 with the lower face of the door. A link 20 is pivoted to the center of the bar 15 and has its other end pivoted to a link 21 which is pivoted at 22 to an inner wall of the casing. A link 23 is pivoted to the link 20 adjacent the lower end of said link and the outer end of link 23 is curved and pivoted 100 105 110

to a lever 24 which is pivoted to a wall of the case at its lower end and is arranged to pass between the toothed members 14 when the door is open. A spring 25 is fastened to 5 said lever 24 and to a bracket 26 in the case and tends to hold the parts in their forward position with the door closed, as shown in Figure 6. A coin chute 27 is formed in the window 3 in such a manner that a coin inserted into the same will pass into the space between the members 14 and engage some of the teeth of said members so that said coin will bridge the space between the members, as shown at A in Figures 5 and 6. Then 10 the handle 9 is turned to pivotally rotate the roller 7 which will cause the coin to press against the bar 15 and force it towards the rear of the case. The pin and slot connection of the bar with the case will cause the 15 bar to move upwardly as it moves rearwardly and thus it will swing the door 4 upwardly to open position, as shown in Figure 5. During this action the links will cause the lever 24 to move within the space 20 between the members 14. With the door in open position a portion of the strip 6 will be exposed through said door so that advertising matter can be written or otherwise placed on this exposed portion. When the 25 parts reach open position further movement of the roller is impossible and after the advertisement has been placed on the strip the handle is turned in an opposite direction and this will cause the coin to strike the lever 24 and move it to its forward position and this movement of the lever through the 30 links will return the bar 15 and the door 4 to their first position with the door closed. The coin will then drop from the roller upon 35 the bottom of the casing and then the door will remain closed until another coin is introduced into the slot. The handle and roller are then free to be turned to bring any part of the strip in front of the transparent 40 member 2.

Thus I have produced simple means for

placing advertising matter on a strip contained within a casing with coin controlled means for preventing access to the strip until a suitable coin has been dropped into 50 the device.

It is thought from the foregoing description that the advantages and novel features of my invention will be readily apparent.

I desire it to be understood that I may 55 make changes in the construction and in the combination and arrangement of the several parts, provided that such changes fall within the scope of the appended claims.

What I claim is:—

1. In a coin control device, a movable member, a slidably supported bar connected with the same, a rock shaft having coin receiving slots therein, means permitting the shaft to be rocked to bring a coin held in 60 some of the slots against the bar to move the same to actuate the member, a pivoted lever adapted to be engaged by the coin on the reverse movement of the rock shaft and means for connecting said lever with the bar 65 to return the bar and the member to which it is connected to their normal positions.

2. In a coin controlled apparatus including a casing and a door therein, a slotted bar connected with the door, pins passing 70 through the slots therein and engaging the casing for slidably supporting the bar on the casing, a rock shaft in the casing having an annular groove therein with coin receiving slots in the side walls of the groove, a handle for moving the shaft in one direction to bring a coin in some of the grooves against the end of the bar to move the same longitudinally to open the door, a pivoted lever in the casing adapted to be engaged by the 75 coin on the reverse movement of the rock shaft and links connecting the lever with the bar for returning the parts to their normal positions when the lever is operated by the coin.

MILTON M. BETTERLY.
